UNITED STATES PATENT OFFICE.

ALFRED HONS AND SILAS E. MARTZ, OF BERWICK, PENNSYLVANIA.

TROLLEY-GUARD.

No. 926,565.

Specification of Letters Patent.

Patented June 29, 1909.

Application filed June 18, 1908. Serial No. 439,182.

To all whom it may concern:

Be it known that we, ALFRED HONS and SILAS E. MARTZ, citizens of the United States, residing at Berwick, in the county of 5 Columbia and State of Pennsylvania, have invented certain new and useful Improvements in Trolley-Guards, of which the following is a specification.

The present invention has for its object to 10 devise a simple and efficient trolley-guard for preventing the trolley-wheel from running off the wire.

The wheels now in use are made with a deep groove to receive the trolley-wire, but 15 this is not sufficient to prevent the wheel from running off the wire at times. As we employ a device to retain the wheel in its place it is not necessary to make such a deep groove in our wheel and hence we can use a 20 thinner and, therefore, lighter wheel.

The invention further consists of the novel features and details of construction which hereinafter will be set forth, illustrated, and claimed.

25 Referring to the drawings forming a part of the specification: Figure 1 is a perspective view showing the device applied. Fig. 2 is a side view of the same. Fig. 3 is a front edge view. Fig. 4 is a plan view.

30 Corresponding and like parts are referred to in the following description and indicated in all the views of the drawings by the same reference characters.

In carrying out our invention we provide 35 an ordinary harp 1, provided with a stem 2, adapted to be secured to a trolley-pole in any suitable manner. The harp 1 carries a trolley-wheel 4, mounted to rotate on the pivot-bolt 5.

40 Our invention consists of guard-arms 7, mounted at each side of and projecting out beyond the peripheral flanges of the trolley-wheel 4, said arms being pivotally secured at their lower ends by the bolt 5. The guard- 45 arms 7 consist of thin portions 7^a, which are thickened as at 7^b, and terminate in inwardly extending projections 7^c which are beveled and taper to a point, the points meeting directly above the trolley-wire as shown. Strong wire springs 8 having coils 8^a intermediate their ends, are secured, one on each outer side of the guard-arms 7, by the bolt 5 passing through said coils, the lower ends 8^b of said wires being held by 50 studs 3 located on the harp 1, and the upper ends being fastened to the upper part of the

guard-arms 7 preferably by passing the ends through said guards as shown at 8^c in Fig. 3. The springs 8 exert an inward pressure on the guards. The forward movement of the 60 arms is limited by stops 10 on the harp 1, and in their backward movement the guards are spread by means of cams 11, so as to clear the trolley-wire 9.

The pivot-bolt, or axle, 5 is prevented from 65 longitudinal movement by washers 6 and pins 6^a which are arranged upon opposite sides of the harp.

The usual contact springs 12 are interposed between the sides of the trolley-wheel 70 and the sides of the harp, said springs being connected at their lower end to the harp.

In practice the guard-arms normally occupy a vertical position with their inner extensions over the trolley-wire. By reason 75 of the guards being loosely mounted upon the pivot-bolt 5 they are adapted to move both axially and laterally, thereby adjusting themselves to different relative positions of the trolley without producing strain or binding. In the progress of a car when the trolley-wheel comes to a corner, or to any other place where there are cross-wires, brackets, suspending devices, or guy-wires, the arms will meet said obstructions so as to 85 cause the guard-arms to be pressed downwardly when the aforesaid arms engage the cams and are spread.

From the foregoing specification it will be understood that we provide a trolley-guard 90 which while simple in construction, is at the same time effective and will prevent the trolley-wheel, to which one is applied, from leaving the wire.

Having thus described the invention, what 95 is claimed as new is:

1. In combination with a trolley comprising the usual harp, trolley-wheel and axle, guard-arms pivotally mounted upon opposite ends of the axle upon opposite sides of the 100 trolley-wheel, and having their upper ends provided with inwardly extended projections to overhang the trolley-wheel, springs co-operating with the guard-arms to hold the same in normal position, and cams at the 105 sides of the harp to engage with said guard-arms and effect a spreading thereof when said arms are turned from a normal position by engagement with a frog or other obstruction in their path. 110

2. A trolley comprising a harp having its sides provided with stops and cams, a trolley-

wheel mounted in the harp, and spring actuated guard-arms at opposite sides of the trolley-wheel and free to move axially and laterally and held in normal position by the
5 said stops and spring and adapted to be spread laterally when meeting with an obstruction by riding upon the aforesaid cams.

In testimony whereof we affix our signatures in presence of two witnesses.

ALFRED HONS. [L. S.]
SILAS E. MARTZ. [L. S.]
